Delos S. Haynes, ATTORNEY.

UNITED STATES PATENT OFFICE

CLIFTON JOHN PRATT, OF ST. LOUIS, MISSOURI

MANUFACTURE OF HIGH-COMPRESSION AUTOMOTIVE DISTILLATE

Application filed July 13, 1927. Serial No. 205,283.

This invention relates to a method of and apparatus for distilling oil and with regard to certain more specific features, to the method of and apparatus for converting crude oil 5 into an improved automotive distillate.

Among the several objects of the invention may be noted the provision of a process and apparatus for the conversion of a liquid hydrocarbon series having a given fractional 10 gravity distillation range into a liquid hydrocarbon series having a different fractional gravity distillation range; the provision of means for converting crude oil, or any fraction made therefrom into the maximum 15 amount of automotive distillate resembling the present United States Motor Specification gasoline with the admixture of not less than forty percent (40%) of coal tar benzol; and the provision of means of the class described 20 which produces a minimum amount of residual oil, coke and gas.

One of the salient objects of the invention is to accomplish the desired conversion at substantially atmospheric pressure within the 25 system, thereby eliminating many undesirable features of previous systems.

Another object of the invention is to manufacture an automotive distillate containing the maximum amount of anti-knock properties commercially obtainable from the hydrocarbons undergoing conversion. Other objects will be in part obvious and in part 30 pointed out hereinafter.

The invention accordingly comprises the 35 elements and combination of elements, features of construction, and arrangements of parts which will be exemplified in the structure hereinafter described, and the scope of the application of which will be indicated in the following claims.

In the accompanying drawing, in which is illustrated one of various possible embodiments of the invention, the figure illustrates 40 diagrammatically the relationship between the elements of the system.

Corresponding reference characters indicate corresponding parts throughout the single view of the drawing.

Referring now more particularly to the 45 drawing, the indicia A illustrates a supply

tank containing any liquid hydrocarbon which may be crude petroleum or any fraction made therefrom. Numeral 1 illustrates a suction line on which is located valve 2 through which the liquid hydrocarbon, hereafter referred to as oil, is delivered to suction side of pump 3. The oil is discharged through line 4 and such quantity as desired is delivered by a regulating valve 5 in line 6 into a cooling coil 7, located inside a dephlegmator B. The oil passing through coil 7 absorbs heat from certain vapors (to be described) in dephlegmator B and passes from the dephlegmator to a common header line through coil outlet line 8.

By manipulating the regulating valve 9, any desired quantity of oil may be admitted from pump discharge line 4 through line 10 into a cooling coil 11 located in a lower oil reservoir section R of the dephlegmator B. By regulating a valve 12 in the line 13, any desired quantity of the oil passing out of coil 11 may be admitted to a common header to a furnace heating coil 17. By regulating valve 14 any desired quantity of oil may be returned through line 15 to supply tank A.

It is to be understood that there is a possibility that an excess amount of oil will necessarily be pumped through coil 11 above the required amount to be fed to the system 80 in addition to the oil fed to the system through coil 7. This excess amount can be returned direct through line 15 to supply tank A or it could, if desired, be made to pass through a cooling coil before returning to 85 the supply tank A.

Line 16 is a common header through which oil is delivered from lines 8 and 13 to heating coil 17, located in preheating furnace C. Valve 18 is located at the outlet of coil 17 and 90 is used, if necessary, to prevent the oil being delivered under substantial pressure through line 19 into the expansion chamber D. The purpose of this is to prevent pressure from building up in the expansion chamber D.

The vapors from expansion chamber D leave the vessel at a point near the top through vapor line 20, which terminates as a reboiling coil 21, near the bottom of the upper fractionating section S of dephlegmator B. The ob- 100

ject of this coil is to re-distill any light vapors that may be entrained in the reflux condensate from the upper portion of the fractionating section of dephlegmator B.

- 5 The residual oil or tar which collects in the bottom of expansion chamber D is withdrawn through line 22 and delivered to a cooling coil 23, submerged in water contained in cooling box E. A valve 24 at the outlet 10 of the cooling coil regulates the liquid level in expansion chamber D and delivers the desired amount of oil to be withdrawn from the system through line 25 to a suitable storage tank, not shown on the drawing.
- 15 It is to be understood that this residual oil may gravitate to storage or may be withdrawn by means of a pump.

Inside the dephlegmator B in the top of the fractionating section S of the vessel, located 20 below cooling coil 7 and above the re-boiler coil 21, are located a plurality of baffle plates 26, which may be of any desired type to provide intimate contact between liquid and vapors undergoing treatment.

25 Numeral 27 illustrates a diaphragm separating the upper fractionating section from the lower oil reservoir section of dephlegmator B. Numeral 28 illustrates an overflow nozzle adapted to maintain a liquid level in 30 the upper fractionating section S. It is to be understood that this nozzle may extend, if desired, above or into the re-boiler coil 21 (see for example the dotted lines).

It is to be understood that the dephlegmator B may be divided into a plurality of fractionating and reservoir sections, or the dephlegmator may be composed of several separate fractionating and dephlegmator sections with proper outside connections to insure the 40 correct functioning of the apparatus. In other words, the fractionating section S and the reservoir section R may be formed as separate units, properly interconnected by suitable lines.

45 The liquid reservoir section R of dephlegmator B is cooled to any desired degree above atmospheric by the oil passing through coil 11. The cooled oil in reservoir R provides the precracked charging stock, which is withdrawn through suction line 29 by means of 50 pump 30 and is discharged through line 31 to a heating coil 32 of small cross-sectional area in a cracking furnace F. Substantially atmospheric pressure is used in the coil 32; that is, the pressure is substantially only that 55 necessary to overcome the frictional resistance of the coil.

A valve 33, located at the outlet of heating coil 32, can be used if necessary to prevent cracked oil being delivered under pressure through line 34 into a heat exchanger coil 35, located at a point near the bottom of the expansion chamber D. The object of this exchanger coil 35 is to reboil all light distillates from the residual oil in the bottom of

expansion chamber and at the same time reduce the temperature of the oil entering the expansion chamber from the cracking furnace coil. Another purpose of this is to prevent coking.

70 A plurality of baffle plates 36 are placed inside the expansion chamber above exchanger coil 35 in order to provide intimate contact between the liquid and vapors discharged through line 19 and the vapors discharged from exchanger 35. It is to be understood that the heavy vapors discharged into expansion chamber from line 19 will absorb a certain amount of the lighter vapors delivered to the expansion chamber conditioner 75 from coil 35.

75 It can be seen that the vapors from both precracking coils 17 and treating coil 32 blend and pass out of the expansion chamber D through the line 20, terminating in coil 21 into fractionating section of dephlegmator B. It is a function of the fractionating section of dephlegmator B to separate out the desired fraction of oil vapors for automotive consumption which leave the dephlegmator 90 through vapor line 37 at a point near the top. These vapors pass through condenser coil 38, submerged in water contained in condenser box G. The condensed vapors and non-condensable gas pass out through line 39 into 95 gas separator H on which is located liquid level gauge 40. The non-condensable gas is withdrawn through line 41 at a point near the top of gas separator H by means of pump or 100 blower 42, which discharges the non-condensable gas through line 43 either to an absorption plant for the further recovery of automotive distillate or the non-condensable gas may be used as fuel, for the furnaces F and C. By opening valve 44 automotive distillate 105 may be withdrawn from the bottom of gas separator H and delivered to a suitable storage tank (not shown) through line 45. It is to be understood that the automotive distillate may either gravitate to storage or may 110 be withdrawn by means of a pump.

110 Numerals 46 and 46' represent fuel burners of a conventional type, which supply the products for combustion to preheating and cracking furnace C and F, respectively. 115 Flanged manholes 47 and 47' on expansion chamber D and flanged manholes 48 and 48' on dephlegmator B provide a means of cleaning and repairing the interior of either vessel.

120 The charging stock supply tank A will be substantially at atmospheric temperature. The charging stock after passing through the cooling coil 7 and 11, enters coil 17 in the pre-heating furnace at a temperature of the order of 400° Fahrenheit, which is low enough to prevent substantial coking. The temperature of the oil entering the preconditioner through line 19 is of the order of 800° Fahrenheit. The cooled charging stock from the lower reservoir section R of dephlegmator B en-

temperature of the order of 250° Fahrenheit and leaves the cracking coil through line 34 at a temperature above 1100° Fahrenheit. The vapors from expansion chamber D admitted to dephlegmator B through vapor line 20, enters the dephlegmator at a temperature not to exceed 800° Fahrenheit. The vapors leaving the dephlegmator through line 37, when preparing the end-point distillate for the market should register a temperature of not more than 410° Fahrenheit. The gravity, rather than the temperature, will determine the quantity of residuum to be withdrawn from the expansion chamber through line 22. With the proper velocities through the heating coils the above conditions will treat the oil in the desired manner without the accumulation of an appreciable amount of carbon within the system and with the production of the least possible amount of non-condensable gas.

The temperature in the preheating furnace C is low enough to prevent coking of the crude oil, which tends to coke at lower temperatures than the recycled or precracked stock. Conversely, the precracked stock, from which the residuums and coke-forming constituents have been removed in the expansion chamber D, are subjected to a higher temperature in the cracking coil 32 without coking therein. The cracked vapors from the coil 32 can be brought to a temperature such that they will, upon contacting with the films of preheated crudes in the vaporizing chamber D, crack and further vaporize said preheated crudes, leaving as a liquid in said chamber D the residuums and coke-forming constituents. By the term "coke-forming constituents" herein is meant such heavier fractions or residuums or the like of the crude oil or charging stock as are adapted to coke under the high temperature cracking operation described. The point is that the crude stock and recycled or precracked stock are each made to pass through regions at different temperatures. From the crudes, therefore, in the vaporizing chamber D is formed a precracked stock, devoid of residuums and coke-forming constituents, which is subsequently subjected to high temperature cracking without occasioning coke formation in the high temperature still or cracking furnace F.

It will be seen from the above that the above process involves two heating stages whereby coking is prevented and consequently time saved. Furthermore, excessive gas production is prevented by absorption. Another point is that the product is blended hot and in the vapor stage.

In view of the above, it will be seen that the several objects of the invention are achieved and other advantageous results attained.

As many changes could be made in carry-

ing out the above constructions without departing from the scope of the invention, it is intended that all matter contained in the above description or shown in the accompanying drawings shall be interpreted as illustrative and not in a limiting sense.

I claim:

1. The process of treating hydrocarbons which comprises preheating said hydrocarbons to a temperature insufficient to coke the heavier constituents thereof, subjecting said preheated hydrocarbons to intimate contact with cracked vapors of recycled hydrocarbons whereby said preheated hydrocarbons are vaporized and partially cracked, and the coke-forming constituents of said preheated hydrocarbons are removed therefrom as liquids, comingling the vapors generated from said preheated hydrocarbons and said cracked vapors of recycled hydrocarbons, separating said comingled vapors into lighter constituents and heavier constituents, subjecting said heavier constituents to a vapor phase cracking operation in a stream of restricted cross-sectional area at substantially atmospheric pressure, and recycling said cracked vapors into indirect heat-exchange relationship with said heavier, coke-forming constituents of said preheated original hydrocarbons, and then into intimate contact with said preheated original hydrocarbons.

2. The process of treating hydrocarbon oils which comprises preheating said hydrocarbon oil, subjecting said pre-heated oil to a preliminary cracking operation whereby coke-forming constituents are removed therefrom in a liquid form, said cracking operation being conducted at substantially atmospheric pressure, said cracking operation being effected by filming said preheated oil and intimately contacting the same with cracked oil vapors to form precracked vapors, partially condensing said precracked vapors to a pre-cracked oil, subjecting said pre-cracked oil to a vapor phase cracking operation without substantial coke formation, and bringing the cracked vapors into contact with said preheated oil to crack said preheated oil, and removing light cracked hydrocarbon vapors and condensing the same.

3. The process of treating hydrocarbon oils which comprises subjecting said hydrocarbon oil to a preliminary cracking operation whereby coke-forming constituents are removed therefrom in liquid form, said cracking operation being conducted at substantial atmospheric pressure, said cracking operation being effected by filming said hydrocarbon oil and intimately contacting the same with cracked oil vapors to form precracked vapors, partially condensing the precracked vapors to a precracked oil, maintaining said precracked vapors and at least part of said precracked oil in indirect heat-exchange relationship, subjecting said precracked oil to

a vapor phase cracking operation without substantial coke formation, and bringing the cracked vapors into contact with said hydrocarbon oil to crack said hydrocarbon oil, and removing light cracked hydrocarbon vapors and condensing the same.

In testimony whereof, I have signed my name to this specification this 11th day of July, 1927.
